UNITED STATES PATENT OFFICE

158,496

COMBINED SACHET FIGURE AND CONTAINER THEREFOR

Albert H. Newman, Chicago, Ill.

Application September 1, 1948, Serial No. 148,408

Term of patent 3½ years

(Cl. D86—10)

To all whom it may concern:

Be it known that I, Albert H. Newman, a citizen of the United States, residing at Chicago, in the county of Cook and State of Illinois, have invented a new, original, and ornamental Design for a Combined Sachet Figure and Container Therefor, of which the following is a specification, reference being had to the accompanying drawing, forming part thereof.

In the drawing:

Fig. 1 is a top plan view of a combined sachet figure and container therefor, showing my new design;

Fig. 2 is a perspective view thereof, and

Fig. 3 is a side elevational view thereof.

I claim:

The ornamental design for a combined sachet figure and container therefor, as shown.

ALBERT H. NEWMAN.
